UNITED STATES PATENT OFFICE.

HARRY KUZYK AND FRED MANDZUK, OF SMOKY LAKE, ALBERTA, CANADA, AS
SIGNORS OF ONE-HALF TO PETRO STACHARUK, OF SMOKY LAKE, ALBERTA,
CANADA.

AUTOMATIC GATE.

Application filed December 28, 1923. Serial No. 683,118.

To all whom it may concern:

Be it known that we, HARRY KUZYK and FRED MANDZUK, citizens of Ukraine, residing at Smoky Lake, in the Province of Alberta and Dominion of Canada, have invented certain new and useful Improvements in Automatic Gates, of which the following is a specification.

This invention relates to certain new and useful improvements in automatic gates and relates to that type of gate that is automatically opened by the weight of a vehicle upon a hinged platform or trip associated with operating mechanism for the gate.

15 The primary object of the invention is to provide an automatic gate especially designed for farm use wherein a pair of horizontally sliding gate sections are normally retained in closed abutting relation by weight devices associated therewith and are adapted to be shifted to open positions by the weight of a vehicle passing over operating mechanism for opening the gate sections.

20 A further object of the invention is to provide a lock device for retaining the gate sections in closed position and having operating means associated therewith that are rendered operable for releasing the lock mechanism in advance of operating the devices for opening the gate.

25 With the above and other objects in view as the nature of the invention is better understood, the same consists of the novel form, combination and arrangement of parts 30 hereinafter more fully described, shown in the accompanying drawings and claimed.

In the drawings, wherein like reference characters designate corresponding parts throughout the several views,

40 Figure 1 is a front elevational view, partly in section of an automatic gate constructed in accordance with the present invention, showing the gate sections in their closed and interlocked engagement,

45 Figure 2 is a top plan view of the gate mechanism showing the releasing means for

the latch bolt that retains the gate sections in closed position,

Figure 3 is a central vertical cross-sectional view through the gate construction, 50

Figure 4 is a detail sectional view taken on line IV—IV of Figure 2,

Figure 5 is a cross-sectional view taken on line V—V of Fig. 2 showing the releasing mechanism for the latch bolt carried by 55 one of the gate sections,

Figure 6 is a vertical cross-sectional view taken on line VI—VI of Fig. 1,

Figure 7 is a horizontal sectional view taken on line VII—VII of Fig. 4 showing 60 the meshing gears for shifting the gate sections, and

Figure 8 is a fragmentary perspective view of one end of the vertically shiftable bar to which the trip platforms are hingedly 65 connected.

Referring more in detail to the accompanying drawings, there is illustrated an automatic gate embodying a supporting frame structure that includes spaced parallel channel frames 1 and 2 with outwardly directed housings 3 disposed midway the ends thereof, while perpendicular guide frames 4 and 5 extend upwardly from the channel frames 1 and 2 at the inner ends of the lateral housing 3. A horizontal track rail 6 extends between the upper ends of the vertical frame bars 4 and 5 supporting horizontally sliding gates in a manner to be hereinafter described. 70

75 A bar 7 is vertically shiftable in the frame structure, the same being guided in its movements by the opposite ends thereof that extend between the side bars of the vertical frame members and into the inner ends of the lateral housings 3, the bar 7 being normally retained at its limit of upward movement by the weights 8 attached to the cables 9 passing over pulleys 10 that are supported at opposite ends of the track rail 6, the 80 cables then traveling downwardly for attachment as at 11 to the upper end of track 85

bars 12 carried by the opposite ends of the bar 7 as clearly shown in Figs. 1 and 8. As shown more clearly in Fig. 3 a trip platform 13 is associated with each side edge of the vertically shiftable bar 7, the inner end of each platform being pivotally mounted as at 14 to said bar while the outer lower corner edges of each platform have a pin and slot connection 15 with the outer adjacent ends of the horizontal channel frames 1 and 2 of the frame structure. The frame structure includes a base bar 16 extending between the side channel frames 1 and 2 intermediate the ends thereof that support shock absorbing springs 17 disposed beneath the vertically shiftable bar 7 for cushioning the downward movement thereof when a vehicle passes over the trip platforms 13.

A pair of gates is horizontally slidably mounted between the spaced bars of the vertical side frames 4 and 5, each gate being of rectangular formation in side elevation and including upper and lower rails 18 and 19 and inner and outer end rails 20 and 21. The inner end of each upper gate rail 18 carrying an upwardly directed arm 22 that supports a track roller 23 at its upper end that rides upon the track rail 6, bearing rollers 24 being journaled between the side bars of the vertical side frames 4 and 5 and in engagement with the upper rails 18 of the gate frames. The lower rails 19 of the gate frames are provided with ratchet teeth 25 upon the lower sides thereof that mesh with a relatively large gear wheel 26 journaled upon the shaft 27 that is mounted in the side walls of the housing 3, the shaft 27 further supporting a pinion 28 that is fixed to the large gear 26 and is in turn in mesh with the gear 29 journaled on the shaft 30 between the side bars of the vertical frame members 4 and 5, the gears 29 meshing with the rack bars 12 carried by the vertically shiftable bar 7.

To retain the gate sections in a locked condition when the same are in closed abutting relation as illustrated in Fig. 1, the inner end rail 20 of one gate frame is provided with a keeper socket 31 into which the operating end of a latch bolt 32 carried by the end rail 20 of the other gate section is received, the latch bolt 32 being shifted to a released position by a link 33 that is attached to a crank portion of the shaft 34 that is journaled at its ends in the end rails 20 and 21 of the latch bolt supporting gate section. As shown in Fig. 6, the vertical frame bar 4 has a lever 35 pivotally supported thereon, one end of the lever 35 having a link connection 36 with the crank shaft 34, while the other end of said lever 35 has a relatively long link connection 37 that is eccentrically connected at its lower end to the disk 38 journaled upon the shaft 39 that is supported in the side bars of the

channel frame member 1. A triangular plate 40 is pivotally mounted upon the cross shaft 41 in the channel frame member 1, one corner of the plate 40 having a link connection 42 with the disk 38, while a coil spring 43 extends between the shaft 39 and plate 40. A link 44 extends between the plate 40 and the crank end 45 of a trip rod 46 that is journaled between the channel frame members 1 and 2, the trip rods 46 being positioned above the trip platform 13 while a coil spring 47 connects the crank portion 45 of the trip rod to the adjacent end wall of the channel frame member. A similar trip rod 46^a is disposed at the opposite side of the gate frame structure and has a relatively long link rod connection 48 with one corner of the plate 40 as clearly shown in Figs. 2 and 5.

When a vehicle approaches either of the trip platforms 13, the front wheels thereof will first engage the trip rods 46 or 46^a, causing a partial rotation of the disk 38 against the spring tension 43 and 47 thereon, and through the link and lever connection with the latch bolt 32, the latter will be elevated from its keeper socket 31 in the opposed gate section. The weight of a vehicle upon either of the trip platforms 13, will cause the raised ends thereof to be lowered and carry therewith the bar 7, such movement causing the rack bars 12 carried by the ends of the bar to rotate the train of gearing with the result that the outermost gears 26 engaging the rack teeth 25 upon the gate sections, shift the gate sections laterally or horizontally slide the same between the spaced bars of the vertical guide frames to an open position and against the power of the weight 8, the gate sections being further guided in their movement by the guide rods 49 extending from the vertical frame members 4 and 5 to the outer ends of the housings 3 as clearly shown in Fig. 1, vertical movement of the bar 7 being guided by the rods 50, shown more clearly in Figs. 1, 3 and 4. When pressure is relieved on the trip platform 13, the weights 8 associated with the rack bars 12 at the ends of the vertically shiftable bar 7, will move the bar 7 and the inner ends of the trip platform 13 connected thereto upwardly, causing a reverse rotation of the gear train and a consequent closing movement of the gate sections, the latch bolt 32 automatically moving into the keeper sockets 31 in the opposite gate sections.

While there is herein shown and described the preferred embodiment of the present invention, it is nevertheless to be understood that minor changes may be made therein without departing from the spirit and scope of the invention as claimed.

What is claimed as new is:—
In an automatic gate, a frame structure,

horizontally sliding gates supported on the frame structure, a vertically shiftable bar disposed beneath the gates, platforms respectively hinged at their inner ends to opposite sides of the bar, means for holding the gates in closed abutting relations with the bar in an elevated position, operative connections between the bar and gates causing opening movement of the gates when the raised ends of the platforms are lowered, the operative connections between the bars and gates including a vertical rack bar carried by each end of the bar, rack teeth upon

the lower edge of each gate and meshing gears interposed between the rack bars and 15 rack teeth.

In testimony whereof we affix our signatures.

HARRY ^{his} X KUZYK.
